DESIGN FOR A BADGE OR THE LIKE

Mary Trude, Los Angeles, Calif., assignor to Women's Ambulance and Defense Corps, a corporation of California

Application December 26, 1942, Serial No. 109,144

Term of patent 14 years

(Cl. 29—2)

To all whom it may concern:

Be it known that I, Mary Trude, a citizen of the United States of America, residing at Los Angeles, in the county of Los Angeles, State of California, have invented a new, original, and ornamental Design for a Badge or the like, of which the following is a specification, reference being had to the accompanying drawing, forming a part thereof.

Fig. 1 is a front elevational view of a badge or the like showing my new design; and

Fig. 2 is an edge view thereof.

I claim:

The ornamental design for a badge or the like, as shown.

MARY TRUDE.
